REVERSIBLE GARMENT BUTTON

Emanuel A. Kostopoulos, Drexel Hill, Pa., assignor to the
United States of America as represented by the Secretary
of the Army

Application December 23, 1953, Serial No. 28,193

Term of patent 14 years

(Cl. D17—2)

(Granted under Title 35, U. S. Code (1952), sec. 266)

FIG. 1.

FIG. 2.

FIG. 3.

FIG. 4.

FIG. 5.

FIG. 6.

To all whom it may concern:

The invention described herein, if patented, may be manufactured and used by or for the Government for governmental purposes, without the payment to me of any royalty thereon.

Be it known that I, Emanuel A. Kostopoulos, a citizen of the United States, residing at Drexel Hill, in the county of Delaware and State of Pennsylvania, have invented a new, original, and ornamental Design for a Reversible Garment Button, of which the following is a specification, reference being had to the accompanying drawing, forming a part thereof.

Figure 1 is a perspective view of one side of a reversible garment button showing my new design;

Figure 2 is a side elevational view of the same;

Figure 3 is a perspective view like Figure 1 but showing the opposite side of the button;

Figure 4 is a transverse, vertical sectional view through the button and showing the same applied to a garment with one face outward;

Figure 5 is a view like Fig. 4 but showing the opposite face outward; and

Figure 6 is a plan view of the button.

The broken lines appearing in Figs. 4 and 5 are for the purpose of illustration only.

I claim:

The ornamental design for a reversible garment button, substantially as shown and described.
